UNITED STATES PATENT OFFICE.

GILMAN W. BROWN, OF WEST NEWBURY, MASSACHUSETTS, ASSIGNOR OF
ONE-HALF TO HAYDN BROWN, OF SAME PLACE.

AUTOMATIC FIRE-ALARM SYSTEM.

SPECIFICATION forming part of Letters Patent No. 506,582, dated October 10, 1893.

Application filed September 1, 1892. Serial No. 444,728. (No model.)

To all whom it may concern:

Be it known that I, GILMAN W. BROWN, of West Newbury, in the county of Essex and State of Massachusetts, have invented certain 5 new and useful Improvements in Automatic Fire-Alarm Systems, of which the following is a specification.

This invention relates to a system for transmitting signals, and is especially designed 10 and adapted to be used as an automatic fire alarm system.

My present invention has for its object, to provide a construction and arrangement of apparatus whereby an annunciator drop preferably of a construction as will be described, may have its magnet coils included in a normally closed branch circuit connected to the main line circuit, in which are located thermostats substantially of the construction 15 shown and described in United States Patent No. 463,608, granted to me November 17, 1891, the branch circuit containing the annunciator drop magnets being without current, while the thermostats remain inactive, but 20 which is adapted to be brought into circuit with the main line battery upon the operation of a thermostat as will be described. The annunciator drop referred to is preferably composed of a pivoted target operated 25 in one direction by a pivoted armature movable between the coils to the electro magnet, the said target being provided with an indication preferably the word "fire" which is normally concealed from view, but which is 30 adapted to be brought into view when the electro-magnet is energized by the operation 35 of a thermostat.

The particular features in which my invention consists, will be pointed out in the claims 40 at the end of this specification.

Figure 1 is a front elevation of an annunciator, provided as herein shown with four annunciator drops having their magnets connected to an electric circuit extended through 45 or over four sections or floors of a building or other structure to be protected. Fig. 2 is a front elevation of one of the annunciator drops shown in Fig. 1; Fig. 3 a top or plan view of the annunciator drop shown in Fig. 50 2; Fig. 4 a sectional detail of the line 4 4, Fig. 3; Fig. 5 a diagram of circuits represent-

ing the annunciator shown in Fig. 1, as connected in circuit with suitable thermostats, located on the different floors of the building or other structure; Fig. 6 a top or plan view 55 of the form of the thermostats preferred by me; Fig. 7, a longitudinal section of the thermostat shown in Fig. 6 on the line 7 7; Fig. 8 an under side view in perspective of the thermostat shown in Fig. 6 with the bottom plate 60 or cover removed, and Figs. 9 and 10 diagrams or circuits to enable the operation of the annunciator to be more readily comprehended.

Referring to Fig. 1, A represents an annunciator case or frame, provided with a door A' having as represented, suitable holes or openings a, there being four such holes herein shown, with which register targets a' of annunciator drops A², there being four such annunciator drops herein shown, which are located within the case A. Each annunciator drop A² may and preferably will be made substantially as shown in Figs. 2 and 3, it consisting of an electro-magnet having two coils 65 a² a³ connected by a yoke a⁴ and front strap a⁵, between which is pivoted a shaft or arbor a⁶ having secured to or forming part of it an armature a⁷ located between the pole pieces a⁸ a⁹ of the electro-magnets a² a³. The pole 70 pieces a⁸ a⁹ have mounted on them magnetic heads 2 3, preferably circular in shape and which are herein shown as separated from the coils of the magnets by insulating washers 4 5, the said magnetic heads extending 75 80 the field of force of the pole pieces a⁸ a⁹ and co-operating with the armature a⁷ mounted to swing or oscillate in a line parallel with the magnetic heads. The target a' is loosely 85 mounted on a screw or stud b, and is adapted 90 to be turned on the stud b as a pivot by an arm or projection b' on the armature a⁷, the target a' normally occupying a substantially vertical position, in which it is maintained by a pin b² on the front strip a⁵ engaging a finger b³ on the said target.

In practice, the annunciator case A, containing as many annunciator drops as there are floors or sections of the building or other structure to be protected, may and preferably 100 will be located near the main entrance of the building, and the electro-magnets a² a³ of

each annunciator drop are connected to one line wire of a main line circuit extended through the building.

Referring to Fig. 5, I have represented in diagram four floors of a building marked respectively, 1, 2, 3, and 4, and have extended through the said building, an electric circuit consisting of the positive wire b^{10} and the negative wire b^{12} of a battery b^{13} .

10 The line wires b^{10} b^{12} on each floor have included in them, a series of thermostatic instruments B' , shown separately in Figs. 6 to 8 inclusive, they being preferably made as shown in said figures.

15 Referring to Figs. 6 to 8 inclusive c represents a porcelain or other insulating base preferably made concaved on its upper side and provided with a detachable bottom c' of insulating material, which is secured to the 20 base c by suitable screw rods c^2 . The base c has secured to its under side two sets of circuit terminals, consisting of metallic springs c^3 c^4 and metallic strips or contact plates c^5 c^6 , the said strips being secured to the insulating base c at one end by suitable nuts c^7 on the threaded rod c^2 , and the metallic springs c^5 c^6 being also firmly secured to the base c by like nuts c^8 . The metallic springs c^3 c^4 are normally secured to the metallic strips c^5 c^6 by 25 soft solder or other fusible connections, and the said springs on their under sides have secured to or forming part of them, hook shaped arms c^9 c^{10} , which project through suitable slots c^{12} c^{13} in the base c , and are adapted to 30 be brought in contact with pole changing circuit terminal strips c^{14} c^{15} secured respectively to the metallic plates c^5 c^6 .

In the operation of the thermostats, effected by a rise in temperature, as by the breaking out of a fire, the fusible connection joining the springs c^3 c^4 to the contact plates c^5 c^6 , become melted or ruptured, and permit the said springs to separate from the said plates and bring the hooked arms c^9 c^{10} into contact 40 with the terminal strips c^{14} c^{15} , thereby reversing the current through the electric circuit, substantially as described in the patent referred to. The electro-magnet a^2 a^3 of each annunciator drop is connected by branch 45 wires d d' to one of the line wires of the metallic circuit, the said branch wires being connected as herein shown, to the positive wire. The electro-magnets a^2 a^3 of each annunciator drop are located in a normally closed branch 50 through which no current flows so long as the thermostats in the main line are in their normal condition and ready for operation as shown in Fig. 9. When this normal condition prevails no current will flow through the 55 magnets of the annunciator drop, because there is no difference of potential between the points at which the branches which include said electro-magnets are connected with the main line. It will be seen therefore that 60 65 the effect of reversing the current by the release of the springs of any thermostat which

is in the main line between the terminals of any annunciator magnet, in effect transfers one terminal of the annunciator magnet from one side of the line to the other, or in other words causes a difference of potential between the two terminals of the circuit through the annunciator magnets, causing the current to flow. To illustrate, let it be supposed that the springs c^3 c^4 of one of the thermostats is operated by the breaking out of a fire. In this case as above described, the magnets c^2 c^3 of the annunciator drop are included in circuit with the battery b^{13} , which circuit may be traced in Fig. 10 as follows, viz: from the 70 positive pole of the battery b^{13} by wire b^{10} to the terminal plate c^6 , thence by the branch wire d through the magnets c^2 c^3 , and wire d' , back to the portion of the wire b^{10} connected to the spring c^4 , thence by the forked arm c^{10} 75 and terminal strip c^{15} to the terminal plate c^5 , thence by the wire b^{12} back to the battery. As soon as the magnets c^2 c^3 are energized as described, the armature a^7 for the annunciator magnets connected in circuit with the particular floor upon which the fire has broken out, is attracted by its magnets a^2 a^3 and moved in the direction indicated by the arrows in Fig. 2, thereby causing the pin b' to throw the target a' over, so as to bring the 85 word fire in front of the opening a , corresponding to the particular floor upon which the thermostat has operated.

The thermostatic system may and preferably will include a signal receiving apparatus, 90 represented as a bell D , which may be operated substantially as described in the patent referred to, but which preferably will be constructed substantially as described in an application, Serial No. 444,729, filed concurrently herewith.

As represented in the drawings, the receiving instrument, is disconnected from the main lines b^{10} b^{12} but may be connected thereto by the switches d^5 .

It will be noticed that the electro-magnets of the annunciator drop are in a normally closed branch circuit, which in practice is controlled by the thermostat and which normally is free from current. This arrangement of 115 the annunciator magnets, possesses advantages over other arrangements now commonly employed, in which the annunciator magnets are located in a closed circuit containing a battery, and also in which the annunciator magnets are located in an open circuit. When the annunciator magnets are located in the closed circuit containing a battery, the latter is gradually being used up and requires attention and care, and in the case 120 of the open circuit, a contact must be made to energize the annunciator magnets, which contact is liable to become inoperative, and in an automatic fire alarm system, it is very 125 essential that all parts should be positive and reliable, in their operation.

The magnets of the annunciator drops

should be made of comparatively high resistance, so that they will divert only a small proportion of the current of the main battery.

I do not limit myself to the use of the described improvements for fire alarm purposes, so far as the general system is concerned. The system may be used as a burglar alarm by substituting for the pole changing thermostats any other suitable pole changing or current reversing devices, such as switches which may be operated by the opening of doors or windows or otherwise.

I claim—

1. An alarm or signaling system consisting of the following instrumentalities, viz: a normally closed main line circuit, a normally closed branch circuit normally connected to one side of the main line circuit, an annunciator magnet included in said branch circuit, and a current reversing or pole changing device in the main line circuit constructed, when operated, to reverse the current through the main line and to connect the said branch circuit with the other side of the main line circuit, thereby causing the current to flow through the annunciator magnet, substantially as described.

2. An automatic fire-alarm system consisting of the following instrumentalities, viz: a normally closed main line circuit, a normally closed branch circuit connected to the main line circuit, as described, to obtain uniform potential in said branch circuit, an annunciator magnet in said branch circuit normally inoperative while the potential at the ends of the branch circuit remains unchanged, and a pole-changing thermostat in the main line operated by a rise in temperature to effect a change in potential in the branch circuit and energize the said annunciator magnet, substantially as described.

3. In an automatic fire alarm system, the combination with a main line provided with a normally closed thermostat consisting of spring members c^3 c^4 having projections or arms c^9 c^{10} , terminal plates c^5 c^6 to which the

spring members are normally connected by fusible connections, and pole changing strips c^{14} c^{15} with which the projections c^9 c^{10} co-operate when the thermostat is operated, of an annunciator magnet having its coils included in a normally closed branch circuit d d' , one wire d being normally connected to one of the main line wires on one side of the thermostat and the other branch wire d' being connected to the same main line on the other side of the thermostat, one wire of the said branch circuit being connected to the other main line wire by the operation of the thermostat, substantially as described.

4. The herein described annunciator, consisting of the magnet coils c^2 c^3 having its cores connected by the yoke a and front strap a^5 , a target a' pivoted to the front strap, an armature a^7 pivoted between the coils of the said electromagnets, a stud or pin b' on the armature a^7 to act on the target a' , substantially as described.

5. An alarm and signaling system, consisting of the following instrumentalities, viz:—a normally closed main line circuit; a polarized electro-magnet therein; a normally closed branch circuit normally connected to one side of the main line circuit; an annunciator-magnet included in said branch circuit; and a current-reversing or pole-changing device in the main line circuit, constructed, when operated, to reverse the current through the main line and operate the polarized electro-magnet, and to connect the said branch circuit with the other side of the main line circuit to operate the annunciator-magnet; substantially as described.

In testimony whereof I have signed my name to this specification, in the presence of two subscribing witnesses, this 9th day of August, A. D. 1892.
